PRESSURE APPLYING MEANS FOR CLOTH ROLLS IN LOOMS

William H. Bahan, Greenville, S. C.; Edward F. Bahan, administrator of said William H. Bahan, deceased

Application November 17, 1947, Serial No. 786,473

3 Claims. (Cl. 139—308)

1

This invention relates to the pressure applying means to the cloth roll pin of a loom for holding the roll of cloth thereon in engagement with the sand roll.

It is an object of this invention to provide means for applying pressure to the cloth roll pin of the loom by eliminating the rack and pinion connection heretofore used between a horizontally disposed spring pressed shaft and the upwardly movable members in which the cloth roll pin is mounted and in lieu thereof providing a cylinder or pulley on each end of the spring pressed shaft to which is secured a flexible cord or cable and having the other ends of the flexible cords or cables secured to the lower end of the vertically movable means which support the cloth roll pin in the upper end thereof.

Some of the objects of the invention having been stated, other objects will appear as the description proceeds when taken in connection with the accompanying drawings, in which:

Figure 1 is an end view of a loom and showing the cloth roll mechanism;

Figure 2 is a vertical sectional view taken substantially along the line 2—2 in Figure 1;

Figure 3 is a view similar to Figure 2 but showing the mechanism in position before the roll of cloth has attained large proportions;

Figure 4 is an isometric view of the lower left-hand end of Figure 1 looking toward the left;

Figure 5 is a vertical sectional view through a portion of the mechanism shown in Figure 4, and taken along the line 5—5 in Figure 1.

Referring more specifically to the drawings, the numerals 10 and 11 indicate the side frames of a loom which have a breast beam 12 secured across the top thereof in which is mounted a sand roll 13. Over this sand roll, cloth 14 passes on its way to the cloth roll pin. The lower portions of the side frames 10 and 11 are secured to each other by a bottom girt 15 on which are mounted opposite hand members 16, they being identical and having like reference characters, except that one is opposite hand to the other.

These members 16 are secured at their upper ends by means of bolts 18 to downwardly projecting portions 19 on the breast beam 12. These members 16 have an outwardly and inwardly projecting lug 20 near the lower end thereof and immediately below these lugs, by means of bolts 21, the lower ends of the members 16 are secured to the bottom girt 15.

The members 16 are slotted and have portions 23 and 24 projecting inwardly toward each other and beneath the inwardly projecting portions of

the lugs 20 and the spaced portions 23 and 24, vertically disposed cloth roll pin supporting members 26 are mounted for vertical sliding movement. The members 26 also penetrate suitable holes 27 in the bottom girt 15. Each of these members 26 has a notch 28 at the upper end thereof in which the ends of a cloth roll pin 29 are mounted for rotation. Each of the members 26 has a vertically disposed groove 32 therein, the purpose of which will be presently described.

Mounted on the bottom girt 15 is a bracket 35 having an elongated bearing portion 36 in which is rotatably mounted a shaft 37. This shaft 37 has fixedly secured thereon a longitudinally split worm gear 38 which meshes with a worm 39 rotatably mounted in the bracket 35 and having a crank 41 for imparting rotation to the worm gear 40, such as shown in my prior Patent No. 2,226,277 of December 24, 1940.

20 The hub portion of split gear 38 has adjustably secured thereon a clamping collar 43 to which is secured one end of a torsion spring 44, the other end of the torsion spring being secured to a collar 45 fixedly secured on the shaft 37 by a set screw 46.

25 On each end of the shaft 37 there is mounted a drum or pulley 50, like reference characters applying to the two drums, and these drums have a notch 52 cut in the periphery thereof in the vertical face of which is disposed

30 a bore 54 and in which is secured by means of a set screw 55 one end of a flexible cord or cable 56 which cable extends outwardly and downwardly in the groove 32 and penetrates a substantially transverse bore 57 in the lower end of the member 26, and is secured in position in this bore 57 by any suitable means such as a set screw 58.

35 The sand roll 13 is driven by any suitable means, not shown, to impart rotation to the sand roll and it usually has a roughened surface for imparting rotation to the cloth on the cloth roll pin 29.

40 In the beginning of the formation of a cloth roll, the crank 41 is turned to thus turn the shaft 37 to which is secured the drums 50. The drums 50 wind up the flexible cables 56 to thus raise the members 26 until the members 26 are in substantially fully raised position. Then the cloth is turned around the cloth roll pin a few

45 times to secure it in position and then the crank 41 is turned to press the cloth on the cloth roll pin 29 against the sand roll 13. The crank 41 is continued to be turned until suitable tension is present in the spring 44 and at which time increased tension would cause the collar 43 to slip

on the split gear 38 as well as causing the split gear 38 to slip and rotate on the shaft 37.

In this position the members 26 are moved to their highest position and as the roll of cloth increases in diameter, the members 26 are forced downwardly against the torsion of spring 44 to cause the shaft 37 to rotate within the gear 38 and the collar 43 will slip and rotate around the gear 38 to thereby insure a like tension between the sand roll 13 and the cloth wound about the pin 29 until the roll of cloth C is fully finished, the parts will occupy substantially the position shown in Figures 1 and 2.

It is thus seen that instead of having pinions on the shaft 37 and a rack on the members 26 which give much trouble on account of breaking and becoming marred, or especially on account of lint and grease becoming lodged in the teeth of the pinion and the rack, that I have provided a simple pulley or drum on each end of the shaft 37 with a cable connection between the drums or pulleys and the lower ends of the vertically movable members 26 which support the cloth roll.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a loom having a sand roll, a pair of vertically movable members mounted in the loom and having means for supporting a cloth roll pin in the upper end thereof and having a longitudinally extending groove in their front edges in their lower portions, a transversely disposed shaft mounted in the lower end of the loom and in a plane above the lower ends of the vertically movable members and a torsion spring fixedly secured to a portion of the loom at one end and surrounding said shaft and being secured to said shaft at its other end, means for imparting rotation to the shaft to store force in the torsion spring, each end of said shaft having a drum mounted thereon the peripheries of which are in front of and disposed adjacent said grooves and one end of a flexible cord secured in each of said drums, the flexible cords extending downwardly in said grooves and having their lower ends secured to the lower ends of the vertically movable members for supporting the cloth roll pin.

2. In a loom having a cloth pin on which cloth is rolled after it is woven, said loom having a driven sand roll for contacting the cloth on the cloth pin for rolling the cloth onto the cloth pin, a pair of grooved members, the top ends of which

are adapted to support the cloth pin, a pair of cables connected to the lower ends of the grooved members and extending upwardly along the groove and being secured to a pair of pulleys fixed on the ends of a transversely disposed shaft mounted in the loom, a collar fixed on said shaft to which one end of a torsion spring is secured, a worm and gear connection for imparting rotation to the shaft and to which the other end of the torsion spring is secured and a crank connected to the worm whereby by turning the crank, torsion will be transmitted through the torsion spring to the collar and will thus rotate the transversely disposed shaft and raise the grooved members upwardly to cause the pin to contact the sand roll.

3. In a loom having a cloth pin on which cloth is rolled after it is woven, said loom having a driven sand roll for contacting the cloth on the cloth pin, a pair of grooved members, the top ends of which are adapted to support the pin, a pair of cables connected to the lower ends of the grooved members and extending upwardly along the grooves and being secured to a pair of pulleys fixed on the ends of a transversely disposed shaft mounted in the loom, a collar fixed on said shaft to which one end of a torsion spring is secured, a worm and gear connection for imparting rotation to the shaft and to which the other end of the torsion spring is secured and a crank connected to the worm whereby by turning the crank, torsion will be transmitted through the torsion spring to the collar and will thus rotate the transversely disposed shaft and raise the grooved members upwardly to cause the cloth pin to contact the sand roll, means whereby as the amount of cloth is increased on the cloth pin, the torsion on the spring will cause the transversely disposed shaft to rotate according to the pressure between the roll of cloth and the sand roll to thus allow the cables to move downwardly with the grooved members.

WILLIAM H. BAHAN.
